US00D876951S

(12) United States Design Patent (10) Patent No.: US D876,951 S
(45) Date of Patent: * Mar. 3, 2020

(54) FOOD CARTON

(71) Applicant: Inno-Pak, LLC, Delaware, OH (US)

(72) Inventors: Jonathan D. Sill, Delaware, OH (US);
Steven A. Mayer, Indianapolis, IN (US)

(73) Assignee: INNO-PAK, LLC, Delaware, OH (US)

() Term: 15 Years

(21) Appl. No.: 29/644,833

(22) Filed: Apr. 20, 2018

(51) LOC (12) Cl. 09-03
(52) U.S. Cl.

USPC D9/431; D9/421

(58) Field of Classification Search

USPC D9/414-423, 430-433, 454, 456, 457,
D9/711, 713, 721-722
CPC ... B65D 5/00; B65D 5/02; B65D 5/18; B65D
5/20

Ryan K. Simmons

(57) CLAIM

The ornamental design for a food carton, as shown and described.

DESCRIPTION

FIG. 1 is a perspective view of a food carton showing a new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is a perspective view of the food carton of FIG. 1 showing it in an open configuration;

FIG. 9 is a top plan view thereof;

FIG. 10 is a bottom plan view thereof; and,

FIG. 11 is a perspective view of the food carton of FIG. 1 showing a flap being removed therefrom.

In the drawings the dotted lines are for the purpose of illustrating perforations and form part of the claimed design; and the dash-dash broken lines are for the purpose of illustrating environment only and form no part of the claimed design.

1 Claim, 9 Drawing Sheets
